United States Patent Office.

HANSON COOK, OF NEW BRIDGEPORT, PENNSYLVANIA.

Letters Patent No. 102,373, dated April 26, 1870.

IMPROVED WASHING-MACHINE.

The Schedule referred to in these Letters Patent and making part of the same.

To all whom it may concern:

Be it known that I, HANSON COOK, of New Bridgeport, in the county of Bedford and State of Pennsylvania, have invented a new and useful Improvement in Washing-Machines; and I do hereby declare the following to be a full, clear, and exact description of the same, reference being had to the accompanying drawings which are made a part of this specification; and in which—

Figure 1 is a plan of a washing-machine embodying my invention.

Figure 2 is a central transverse section of the same.

Figure 3 is a plan of the lower rubber.

Similar letters of reference indicate corresponding parts in the several figures.

My invention consists in the arrangement and construction of certain parts, as will be hereinafter more fully described.

In order that others skilled in the art to which my invention appertains may be enabled to fully understand and use the same, I will proceed to describe its construction and operation.

In the drawings—

A represents the tub or box, whose sides preferably slant outward from the bottom, as shown.

The crooked legs B are intended to form a broad base to prevent the tub from tottering or tilting over.

The legs at each end of the box are formed together by cross-pieces C, which form the supports upon which the tub rests, and to which the latter may be screwed or otherwise made fast.

D is a stationary rubber occupying a central position within the box A.

This rubber rests upon the bottom of the tub A, and its rollers d and slats d' are parallel with the longitudinal center of the tub.

The rubber D can be lifted out of the tub, but when in operating position it is held against displacement by the strips E, which are screwed or otherwise fastened to the bottom of the tub, and which fit between the side-pieces d d' of said rubber D.

The rollers and slats of the lower rubber D, as well as those of the upper rubbers F, are similarly or diversely corrugated or furrowed.

The rollers d have iron journals projecting from their ends, and the side-pieces d' of the rubber D have attached to them notched metallic plates G G, which afford bearings for the said journals.

Strips H H, screwed to the side-pieces of the rubber D, confine the journals of the rollers in the notches of the plates G G, and said strips, being readily detachable, enable one or more of the rollers d to be removed and replaced without injury to the rubber.

The slats d' are nailed to the side pieces d', and the slats and rollers are situated at about one-fourth of an inch apart, to allow the water to pass through the rubber.

The rollers d are in close proximity to the bottom of the tub.

The oblique corrugated or furrowed slats of the upper rubber F are connected together by the side-pieces f f, whose bottoms are arcs of the same circle as the tops of the side-pieces d' of the lower rubber.

I I are the side-pieces of a frame to which the operating-handle I' is attached.

These side-pieces I I are let into mortises, and screwed to the side of the rubber F.

The rubber F is mounted to vibrate transversely of the box A, and the rod J, upon which the suspending-frame I I' is supported, has its bearings in the side pieces of the frame K K', which is hinged by means of the rod L to the two pieces M M, which are screwed to the back of the box A.

The suspending rod J should be somewhat below the center of the circle of which the rubbers form an arc, so as to give the upper rubber a drawing action upon the clothes, and cause the ends of said rubber to escape the sides of the box during operation.

It will be observed that inasmuch as both the rubbers D and F, together with the frames I I' and K K', are situated at the center of the tub, the spaces N N at the ends of the latter are left free and unobstructed.

Hence, a very large article may be placed in one of said spaces, and, if the whole of the material requires washing, it may be introduced between the rubbers, washed, and drawn through into the opposite space while the remainder has a chance to soak, preparatory to being washed. Soiled portions of garments or other articles may be thus washed without operating upon other parts.

The side-pieces K K of the supporting-frame extend across the box A, and, by depressing said frame by means of its handle K', the rubber F may be made to exert the desired degree of pressure upon the clothes during operation. The rubber F, being suspended in the manner described, will, of itself, conform to the thickness or bulk of the material to be operated upon.

Having thus described my invention,

What I claim as new, and desire to secure by Letters Patent, is—

The construction and arrangement of the rubber D with rollers having oblique corrugation, and arranged transversely at the middle of the tub, so as to leave spaces N at each end for clothes, &c., and under the rubber for sediment, in combination with the metallic plates G G, and journals, confining-strips H H, and slats d, as shown in fig. 3, the rubber F, the suspended and pivoted frame I K, and tub A, as shown and described.

The above specification of my improved washing-machine, signed this 7th day of May, A. D. 1868.
